S. G. STEVENS

THRESHOLD

Filed Oct. 27, 1923

Inventor

S. G. Stevens.

UNITED STATES PATENT OFFICE.

SYLVESTER GEO. STEVENS, OF DULUTH, MINNESOTA.

THRESHOLD.

Application filed October 27, 1923. Serial No. 671,243.

To all whom it may concern:

Be it known that I, SYLVESTER GEO. STEVENS, a citizen of the United States, residing at Duluth, in the county of St. Louis and 5 State of Minnesota, have invented certain new and useful Improvements in Thresholds, of which the following is a specification, reference being had therein to the accompanying drawing.

10 This invention relates to door openings and has special reference to a removable combination threshold and conduit.

The object of the invention is to provide the simplest means possible for conducting 15 a liquid transverse the lower portion of a door opening, thus rendering it possible to install a steam or hot water system within a house without cutting through the floor to pass a door opening, the threshold resting 20 directly upon the floor boards.

Other objects and advantages of the invention will appear in the further description thereof.

Referring to the accompanying drawing 25 forming part of this application and in which like reference characters indicate like parts:

Figure 1 is a perspective view of one of the improved conduit thresholds;

30 Figure 2 is a fragmentary perspective view of a modified form of same;

Figure 3 is a transverse section centrally of a single chambered threshold; and

35 Figure 4 is a similar view of a double chambered threshold.

1 represents the threshold made preferably of light cast metal, being perfectly flat on the bottom, and substantially arcuate transversely over the top so as to form as 40 little obstruction as possible in a door way, and a threshold over which dirt may be swept, as well as wheeled household articles pass without difficulty.

In the form shown in Figure 1 I have 45 illustrated extensions 2 and 3 at opposite corners, the extension 2 having a hole 4 in the side thereof, while the extension 3 has a similar hole 5 on the top thereof, these

holes being for the installation of the pipe 50 line, whether steam or water, said pipe connections being modifiedly shown at 6 and 7.

In the type shown in Figure 2 a boss 8 is formed upon the corner of the threshold 1 which may prove a desirable form of construction, and in Figure 3 a single chamber 55 9 is shown which of course communicates with the intake and discharge openings, wherever or whatever they may be, while in Figure 4 I have shown double chambers 10 and 11, which as is obvious may communicate with their respective pipe lines and used in the event of it being desirable to return the circuit in the same threshold.

Having thus described my invention, what I claim and desire to secure by Letters Patent, is:

1. The combination with a house door opening, of a hollow threshold therefor extending wholly across the opening on top of the floor and forming part of the frame 70 for the opening, and pipe connecting means, for communication with the interior of the threshold, spaced from either side of the door opening.

2. A hollow conduit threshold of the 75 class described, being flat upon the lower face thereof, the upper surface inclined upwardly from the side edges, and pipe connections at the corners thereof for communication with the interior of the threshold. 80

3. A unitary conduit threshold of the type described shaped to fit within a door opening upon the floor beneath the door and having pipe connections in the corners thereof spaced from the door opening. 85

4. The combination with household heating circulating pipes, of a unitary conduit threshold for doors within the house, said thresholds resting upon the floor within the door openings and pipe connections at the 90 corners of the thresholds spaced from the door openings.

In testimony whereof I hereunto affix my signature.

SYLVESTER GEO. STEVENS.
